UNITED STATES PATENT OFFICE.

JOHN B. DEEDS AND WILLIAM MACK, OF TERRE HAUTE, INDIANA.

SLATE AND WINDOW CLEANER.

SPECIFICATION forming part of Letters Patent No. 287,254, dated October 23, 1883.
Application filed May 4, 1883. (No model.)

To all whom it may concern:

Be it known that we, JOHN B. DEEDS and WILLIAM MACK, of Terra Haute, in the county of Vigo and State of Indiana, have invented 5 certain new and useful Improvements in Slate and Window Cleaners; and we do hereby declare that the following is a full, clear, and exact description of the invention, which will enable others skilled in the art to which it applies 10 to make and use the same, reference being had to the accompanying drawings, and to the letters of reference marked thereon, which form part of this specification.

This invention has for its object to provide 15 a neat and suitable device for scouring and drying slates or windows; and to this end it consists in the construction herein shown, and of which a more-complete description will be given hereinafter, and pointed out in the 20 claims.

In the drawings hereunto annexed, Figure 1 is a perspective view of a fount or reservoir embodying our improvements. Fig. 2 is a side elevation, and Fig. 3 a cross-section 25 thereof.

Reference being had to the letters marked thereon, A represents a reservoir for holding water or other fluid, and which is provided with an inlet, a, for filling it, closed by a suitable stopper or cork, b. Extending longitudinally across the top of said reservoir is a metal strip, B, which is so bent as to form two sides, between which is to be held a drying cloth or rag, e, of as many thicknesses as may be desired, and which can be readily removed when dirty and worn, and a new one placed therein by drawing it tightly between the sides or edges of the metal strips. It will be noticed that the sides of the reservoir converge or 40 incline toward each other at the bottom, and somewhat above the bottom edge, between and within the sides, are secured longitudinally from end to end two metal flanges, c c', one flange overlapping the other and leaving 45 a small space between them sufficient to feed

by natural flow the water therein to a strip or block of felt, D, which is held between the converged sides, and which also serves to strengthen the said sides, and prevents the felt strip from being forced inwardly. The heads d d' at the narrow or bottom end are provided with a point or tooth, which, when the felt has been fitted between the sides, are bent into it and serve to retain and keep it in place. (See Fig. 2.)

It will be obvious that this device may be made of an enlarged size, provided with a handle, and used to wash or cleanse windows.

The operation is apparent. The water or other fluid contained within the reservoir 60 keeps the felt moist by capillary attraction, which is permitted by the small space between the metal flanges c c'. After having washed the slate or window, it is dried by the cloth or rag e on top of the fount.

Having thus described our invention, what we claim is—

1. The slate or window cleaner consisting of the reservoir bent to form converging walls, having secured at its top the bent longitudinal strip B, which serves to hold the drying-cloth, and provided with the metal flanges c c' at or near the bottom, and with a strip or block of felt held by teeth projecting from the end heads, substantially as set forth.

2. The slate or window cleaner consisting of the reservoir bent to form converging walls, having secured at its top the bent longitudinal strip B, and provided with the metal flanges c c' at or near the bottom between the 80 sides, substantially as described.

In testimony that we claim the foregoing as our own we affix our signatures in presence of two witnesses.

JOHN B. DEEDS.
WILLIAM MACK.
